UNITED STATES PATENT OFFICE

2,191,346

ELECTRIC LAMP OR SIMILAR DEVICE AND
METHOD OF MANUFACTURE

Alfred Greiner, Cleveland Heights, Ohio, assignor to General Electric Company, a corporation of New York

Application April 30, 1937, Serial No. 139,912

10 Claims. (CL. 176—29)

My invention relates to electric lamps or similar devices comprising a bulb or envelope having an electric energy translation element sealed therein and to methods of manufacturing the same. More particularly, my invention relates to electric incandescent lamps of the miniature type comprising an electric energy translation element sealed in a glass envelope. Although not limited thereto, my invention is particularly adapted to devices having terminal contact members at different portions thereof, an example of which is the double-ended lamp, the terminal contact members of which are located at opposite ends. The lamp comprising my invention is particularly adapted for use in strings for various decorative purposes such as Christmas tree ornamentation, although it may be used for other purposes, such as automobile, dome or dash lighting.

According to my invention, the lamp bulb is provided with a neck portion to which a metallic thimble or end contact member is sealed. The filament is electrically connected to said thimble and is supported thereby. The bulb is preferably evacuated through a small orifice or aperture in the thimble, and the latter subjected to heat to thereby melt a small quantity of glass, solder or other fusible material disposed adjacent said orifice, which material then flows into and closes the evacuation orifice to thereby hermetically seal the bulb.

In the manufacture of electric miniature lamps of the butt-sealed type a considerable number of parts are necessary, as well as operations, such as basing and exhaust tubulation. It is accordingly one of the objects of my invention to provide an electric miniature lamp simple in construction and consisting of a minimum number of parts. A further object of my invention is the provision of an electric miniature lamp which can be easily and economically made, and which requires a minimum number of operations in the manufacture of the same. A still further object of my invention is to provide a method for the manufacture of electric miniature lamps which method eliminates the customary basing and exhaust tubulation operations heretofore required in the manufacture of lamps of the butt-sealed type.

Other objects and advantages of the invention will appear from the following detailed description of species thereof and from the accompanying drawings, in which:

Figs. 1 to 4 are sectional views illustrating the successive steps involved in the manufacture of a lamp according to one form of the invention;

Fig. 5 is an elevation of the lamp shown in Fig. 4; Figs. 6 and 7 are sectional views of modified forms of thimble construction adapted for use in the lamp shown in Fig. 4; Figs. 8 to 11 are sectional views illustrating the successive steps involved in the manufacture of a lamp according to another form of the invention; Fig. 12 is a perspective view of a modified form of end contact member or thimble construction adapted for use in the lamps shown in Figs. 4 and 11; Figs. 13 to 15 are sectional views illustrating the successive steps involved in the manufacture of a lamp according to still another form of the invention; and Fig. 16 is a view illustrating one form of apparatus suitable for simultaneously evacuating and sealing the orifice of a lamp constructed in accordance with my invention.

Referring to Figs. 1 to 4, illustrating one form of my invention, the lamp there shown comprises a filament mount 10 (Fig. 2) sealed within a glass bulb 11. The filament mount 10 comprises a pair of cylindrical end contact members or metallic thimbles 12, 13, the open ends of which face each other and to which filament support wires 14, 15 are spot welded. The ends of a filament 16 are fastened to the support wires 14, 15. The thimbles 12, 13 are preferably made of chrome iron or some other suitable metal having a coefficient of expansion approximating that of the glass used for the bulb 11. Thimble 13 is provided with a small orifice or aperture 17 in the end wall 18 thereof, through which evacuation of the bulb is effected. It will be noted that the support wire 15, which is spot welded to thimble 13, is formed with a bent portion 19 for the purpose of positioning the weld at the side of and a slight distance away from the orifice 17, thereby insuring the maintenance of such opening.

In assembling the filament mount and bulb, a small quantity of solder, soft melting glass, wax or other similar fusible material 20 which, when heated, will soften and flow, is first placed within the thimble 13 closely adjacent the orifice 17 therein. Although I have shown the fusible material 20 in the form of a bead of glass loosely disposed within the thimble 13, it should be understood that such material may be of any other suitable shape or form, such as a ring, and may be disposed on the outside of the thimble 13 closely adjacent the orifice 17 as well as on the inside thereof. The fusible material having been placed on or within the thimble 13, the entire filament mount 10 is then inserted in the bulb 11 through one of the cylindrical open ends or neck portions 21, 21 of the same. The inside

5 diameters of the neck portions 21, 21 are made slightly larger than the outside diameter of the thimbles 12, 13, thus permitting the latter to slide freely therethrough. After the filament mount has been centered or positioned within the bulb so that the neck portions 21, 21 overlap the thimbles 12, 13 approximately the same amount, both thimbles are fused or sealed to the bulb by the application of heat to the bulb neck portions 21, 21. Pressure may also be applied to the plastic glass to press it firmly against the metal and assure a tight seal therebetween. The lamp is then ready for evacuation, which is preferably carried out in a vacuum chamber, although the same may be effected in any other known manner. After obtaining the necessary vacuum within the bulb, the apertured thimble 13 provided with the fusible material 20 is heated with an induction heater or in any other suitable manner, thereby melting the fusible material which then flows into the orifice or aperture 17, closing the same and hermetically sealing the lamp. The finished lamp produced by the above-described method, and shown in elevation in Fig. 5, can thus be made in a simple and economical manner, requiring a minimum number of manufacturing operations.

10 Figs. 6 and 7 illustrate alternate methods of disposing the fusible material 20 on or within the thimble 13 and closely adjacent the orifice 17 therein. In Fig. 6 the fusible material 20 is in the form of a ring 22 disposed within the thimble 13 and provided with an opening corresponding to the orifice 17 in the thimble. The ring of material 22 is adapted to seat on the end wall 18 of the thimble, and is preferably fastened securely to such thimble by fusion or in some other way. In Fig. 7 the fusible material 20 is disposed on the outside of the thimble 13, and is 15 likewise in the form of a ring 23 having an opening corresponding to the orifice 17. The end wall 18 of the thimble, in this instance, is depressed to form a seat 24 adapted to receive the ring 23 of fusible material, which is securely fastened 20 to such seat by fusion or other means.

25 In Figs. 8 to 11 I have illustrated a different method of manufacturing a lamp comprising my invention. In this instance, the filament mount 25 (Fig. 8) is similar to the mount 18 except for the thimble 13 which, in this case, is first sealed by itself to one of the neck portions 21 of the bulb. Instead of the thimble 13 being attached to support wire 15, a bead of solder or other current-conveying fusible material 26 is securely 30 fastened to the end thereof. The filament mount 25 is inserted within the bulb 11 through the open end 27 thereof and positioned therein so that the bead of solder 26 is disposed in close proximity to the orifice 17 in thimble 13. With the mount 25 in this position, the thimble 12 is then fused or sealed to the surrounding bulb neck portion 21 by the application of heat thereto. The bulb is then evacuated and the thimble 13 subjected to heat in the same manner as described in connection with Figs. 1 to 4. This heat causes the bead of solder 26 to melt and flow into the orifice 17, thereby closing the same and hermetically sealing the lamp. At the same time, the solder or other current-conveying material 26 establishes the electrical connection between the thimble 13 and the lead wire 18 and associated filament mount 25.

35 A modified form of thimble construction is illustrated in Fig. 12, in which a filament supporting tongue 28 extends from the open end

40 of the thimble 12. The end of this tongue 28 is offset inwardly to present a surface 29 extending along the longitudinal axis of the thimble, and to which the filament 16 is adapted to be directly fastened, thereby dispensing with the filament support wires 14 and 15. This particular form of thimble may be used in either of the lamps shown in Figs. 4 and 11.

45 In Figs. 13 to 15, I have illustrated still another method of manufacturing a lamp according to my invention. In this form of lamp the thimbles 12, 12 are inverted so that their open ends extend outwardly of the lamp instead of inwardly, as in the previous forms. The filament mount 30, in this modification, comprises a 50 pair of thimbles 12, 12 and a filament 16 extending therebetween and connected to said thimbles by support wires 14, 14 spot-welded to the end walls 18, 18 of the thimbles. The filament mount 30 is inserted within the bulb 11 through one of the open ends thereof and centered within the same. In this position, one of the thimbles 12 is fused or sealed to the surrounding bulb neck portion 21 by the application of heat to such neck portion. The lamp is then evacuated at 55 the opposite end through the small clearance space provided between the cylindrical walls of the unsealed thimble 12 and the surrounding bulb neck portion 21. Although I prefer to exhaust the lamp in a vacuum chamber, the evacuation 60 may be accomplished, if desired, through an exhaust tube 31 extending from that end of the bulb as yet not sealed to a thimble. This exhaust tube is preferably provided on the bulb by simply leaving a sufficient length of the original 65 glass tube from which the bulb was blown. Evacuation of the bulb having been completed by either of the above methods, the bulb neck portion 21 and associated thimble 12 as yet unsealed, and between which evacuation has taken place, 70 are fused or sealed together by the application of heat to said neck portion 21, thereby hermetically sealing the lamp and completing the same.

75 In the event an exhaust tube 31 has been employed for evacuation purposes, the same is cut or cracked off at the outer end of the associated thimble.

80 Referring to Fig. 16, I have there illustrated a form of vacuum chamber suitable for carrying out the evacuation and orifice-sealing operations 75 referred to above in connection with the lamps shown in Figs. 4 and 11. The evacuating device comprises a housing 32, which may be made of glass, and a base 33 on which the housing is adapted to seat to form a vacuum-tight joint 34 therebetween. The base 33 is formed with an exhaust tube 35 opening into the housing 32, and is further provided with relatively heavy current-supplying leads 36, 36. A lamp-supporting mounting 37 extends between said leads and 85 is formed with a heating coil 38 adapted to receive one of the thimbles of a lamp. The upper extremity of one of said leads 36 is provided with a supplementary lamp supporting bracket 39 adapted to fit over the upper end of the lamp 90 to be exhausted, and insulated from the metallic thimble at such upper end. The unsealed or exhaust end of a lamp of the type shown in Figs. 4 and 11 having been inserted within the heater coil 38, and the supplementary bracket 39 placed 95 over the upper end of the lamp, the housing 32 is then placed over the lamp and positioned on its seat on the base 33 to form a vacuum-tight joint 34 therebetween. The chamber within the housing is then exhausted through the exhaust 100 tube 35.

tube 35. After the required vacuum has been obtained within the chamber, an electric current is passed through the leads 38, 38 to thereby energize the heating coil 38. The heat exerted by 5 said coil on the enclosed metallic thimble of the lamp melts the small mass of fusible material disposed therein, which material then flows into the small evacuating orifice in the end wall of such thimble, thereby closing the same and hermetically sealing the lamp.

What I claim as new and desire to secure by Letters Patent of the United States is:

1. A miniature electric lamp comprising a double-ended glass envelope having tubular end portions, a pair of tubular thimble-shaped metallic end contact members fused along their sides directly to the walls of the end portions of said envelope and forming part of the envelope, and a filament united at its ends to said end contact 15 members and supported solely thereby.

2. A miniature electric lamp comprising a double-ended glass envelope having tubular end portions, a pair of tubular thimble-shaped metallic and contact members fused along their sides directly to the walls of the end portions of said envelope and forming part of the envelope, one of said members being provided with an aperture in the end wall thereof, a filament united at its ends to said end contact members and supported solely thereby, and a quantity of fusible material disposed within said aperture to thereby close the same and hermetically seal said envelope.

3. A miniature electric lamp comprising a double-ended glass envelope having tubular end portions, a pair of tubular thimble-shaped metallic end contact members fused along their sides directly to the walls of the end portions of said envelope and forming part of the envelope, one of said members being provided with an aperture in the end wall thereof, lead wires united to said end contact members, a filament fastened at its ends to said lead wires and supported solely thereby, and a quantity of fusible material disposed within said aperture to thereby close the same and hermetically seal said envelope.

4. A miniature electric lamp comprising a double-ended glass envelope having tubular end portions, a pair of tubular thimble-shaped metallic end contact members fused along their sides directly to the walls of the end portions of said envelope and forming part of the envelope, one of said members being provided with an aperture in the end wall thereof, lead wires electrically connected to said end contact member, a filament fastened at its ends to said lead wires and supported solely thereby, and a quantity of fusible material electrically connecting one of said lead wires to the apertured end contact member and closing said aperture to thereby seal said envelope.

5. A miniature electric lamp comprising a double-ended glass envelope having tubular end portions, a pair of open-ended tubular metallic thimbles fused along their sides directly to the walls of the end portions of said envelope with their

open ends extending inwardly of the same and forming part of the envelope, and a filament united at its ends to said thimbles and supported solely thereby.

6. A miniature electric lamp comprising a double-ended glass envelope having tubular end portions, a pair of open-ended tubular metallic thimbles fused along their sides directly to the walls of the end portions of said envelope with their open ends extending outwardly of the same and forming part of the envelope, and a filament united at its ends to said thimbles and supported solely thereby.

7. A miniature electric lamp comprising a double-ended glass envelope, a pair of open-ended metallic thimbles sealed directly to the ends of said envelope with their open ends extending inwardly of the same, one of said thimbles being provided with an aperture in the end wall thereof, a filament fastened at its ends to said thimbles and supported solely thereby, and a quantity of fusible material disposed within said aperture to thereby close the same and hermetically seal said envelope.

8. A miniature electric lamp comprising a double-ended glass envelope, a pair of open-ended metallic thimbles sealed directly to the ends of said envelope with their open ends extending inwardly of the same, one of said thimbles being provided with an aperture in the end wall thereof, lead wires electrically connected to said thimbles, a filament fastened at its ends to said lead wires and supported solely thereby, and a quantity of fusible material electrically connecting one of said lead wires to the apertured thimble and closing said aperture to thereby seal said envelope.

9. The method of manufacturing electrical devices which consists in forming a filament mount by uniting the opposite ends of a filament to metal thimbles, one of which is provided with an orifice and a quantity of fusible material adjacent said orifice, inserting said filament mount within a container having opposed openings therein by drawing said mount longitudinally through one of said openings until said thimbles are located one adjacent each of said openings, fusing said container to said thimbles, exhausting said container through said orifice, and applying heat to said fusible material to cause the same to flow into and hermetically seal said orifice.

10. The method of manufacturing electrical devices which consists in forming a filament mount by uniting the opposite ends of a filament to metal thimbles, inserting said mount into a double-ended container by drawing it longitudinally through one of the open ends thereof until said thimbles are located one adjacent each of said open ends of the container, sealing one end of said container to one of said thimbles, exhausting said container through the other unsealed end thereof around the other thimble, and fusing the said unsealed end of said container to the said other thimble.

CERTIFICATE OF CORRECTION.

Patent No. 2,191,346.

February 20, 1940.

ALFRED GREINER.

It is hereby certified that error appears in the printed specification of the above numbered patent requiring correction as follows: Page 3, first column, line 24, claim 2, for the word "and" read end; and that the said Letters Patent should be read with this correction therein that the same may conform to the record of the case in the Patent Office.

Signed and sealed this 2nd day of April, A. D. 1940.

Henry Van Arsdale,

(Seal)

Acting Commissioner of Patents.
